UNITED STATES PATENT OFFICE.

LEIGH J. MONSON, OF FARGO, NORTH DAKOTA, AND HERBERT T. BALDWIN, OF DILWORTH, MINNESOTA.

PRINTING DEVICE.

Application filed May 26, 1924. Serial No. 715,968.

To all whom it may concern:

Be it known that we, LEIGH J. MONSON and HERBERT T. BALDWIN, citizens of the United States, residing at Fargo, in the county of Cass and State of North Dakota, and residing at Dilworth, in the county of Clay and State of Minnesota, respectively, have invented certain new and useful Improvements in a Printing Device, of which

10 the following is a specification.

This invention relates to new and useful improvements in printing devices and has reference more particularly to a means for applying a predetermined pattern on a wall or other surface by use of a roller and a printing member detachably supported around the same.

A further object of the invention is to provide a device of the above mentioned character, wherein means is provided for detachably securing a printing member around the roller whereby printing members of various patterns may be used with the same roller.

25 A still further object of the invention is to provide a printing device of the above mentioned character, which is of such a construction as to enable the same to be easily and efficiently operated and will not necessitate the loss of a considerable amount 30 of time and labor in changing the various printing members.

A further object of the invention is to provide a printing device of the above mentioned character, which is simple in construction, inexpensive, strong and durable and furthermore adapted for the purposes for which it is designated.

40 Other objects and advantages of this invention will become apparent during the course of the following description.

In the accompanying drawing forming a part of this specification and in which like numerals designate like parts throughout 45 the same:

Figure 1 is a side elevation of our improved device with a portion thereof shown in section.

50 Figure 2 is a sectional view taken approximately on line 2-2 of Figure 1, and

Figure 3 is a detail plan view of the printing member.

In the drawing wherein for the purpose 55 of illustration is shown the preferred embodiment of our invention, the numeral 1

designates a shaft and carried thereby for rotation therewith is the wooden roller or cylinder 2. The ends of the roller or cylinder are spaced from the ends of the shaft in the manner as shown more clearly in Figure 1 of the drawing. The wooden roller is provided with a longitudinally extending groove 3 and the purpose thereof will hereinafter be more fully described. A weight such as is illustrated at 4 is secured in a longitudinally extending cut out portion 5 provided in the roller therefor and any suitable fastening means such as illustrated at 6 is provided for securing the weight in position within the cut out portion so as to enable the outer face of the weight to be substantially flush with the outer periphery of the roller.

Adapted to extend around the roller is the strip of cloth 7 and secured thereto by any suitable means is the printing member 8 which is formed of sponge-like material. The printing member is of such length as to have the ends thereof spaced from the ends of the cloth fabric 7 in the manner more clearly shown in Figure 3 of the drawing and the purpose of this construction will also be presently described. The sponge-like printing member 8 is preferably secured to the cloth fabric by means of suitable stitching, although it is to be understood that the sponge-like printing member may be vulcanized to a pliable material.

The fabric 7 and the printing member 8 carried thereby is placed around the roller so that the free edges of the cloth fabric will overlap and will further be disposed in the longitudinally extending groove 3 provided in the roller 2. In this manner the adjacent ends of the printing member 8 will abut each other and will cover the groove 3 in the manner more clearly illustrated in Figure 2 of the drawing. For the purpose of securing the fabric and the printing member carried thereby around the roller, we provide the detachable securing means which comprises a spring wire 9.

The wire 9 has its intermediate portion disposed within the groove 3 and engaging the overlapping ends of the fabric cloth 7 and one of the ends of the wire is disposed downwardly as illustrated at 10 adjacent one end of the roller and terminates in a lateral extension 11, the latter extending into a suitable opening provided in a plate 12

which extends over one end of the shaft and is secured to the wooden roller by any suitable fastening means. The manner in which the lateral projection extends into the opening provided in the plate 12 is clearly illustrated in Figure 1 of the drawing.

The opposite end of the wire 9 is disposed downwardly as illustrated at 13 and extends adjacent the opposite end of the wooden roller and also adjacent the plate 14 similar to the plate 12 which is mounted on the opposite end of the shaft and secured to the opposite end of the wooden roller 1 by the fastening means 15. The downwardly extending portion 13 terminates in the hook portion 16 and the latter is received in a suitable notch 17 provided in the end of the shaft 1 in the manner as clearly illustrated in Figures 1 and 2 of the drawing.

The provision of the spring wire 9 enables the fabric 7 to have the printing member 8 carried thereby to be detachably supported around the roller and by disengaging the hook portion 16 from the notch 17 the wire may be released from the groove 3 and the overlapping ends of the fabric so that the latter may be removed and another fabric and printing member with a different printing pattern placed around the roller as is desired.

For the purpose of actuating or rotating the roller and the printing member carried therearound, the handle 18 is provided and the same comprises a single strand of wire which is looped intermediate its ends as shown at 19 and the free ends of the wire are looped around the outer ends of the shaft 1 in the manner as illustrated more clearly in Figure 1. The ends of the shaft are supported in the looped portions of the wire 18 and the roller may freely rotate between the free ends of the wire when in use.

A printing device of the character above described is especially adapted for use in printing various colored patterns on walls and the printing member 8 is supplied with the paint or kalsomine by moving the roller and the printing member carried therearound over a board or the like on which is placed the paint or kalsomine to be applied onto a wall. The printing member being formed of sponge-like material will absorb the paint or kalsomine and by placing the roller against the wall or other sur-

face to be painted and operating the handle, the roller will rotate simultaneously causing the sponge-like printing member to travel over the surface and transfer the pattern thereon onto the wall. In this manner a wall or the like may be painted in any suitable color and with any desirable pattern which is provided by the sponge-like printing member.

The simplicity of our device enables the same to be manufactured at a very low cost and the printing members may be readily interchanged so that various patterns may be used as is desired.

While we have shown the preferred embodiment of our invention, it is to be understood that various changes in the size, shape and arrangement of parts may be resorted to without departing from the spirit of the invention and the scope of the appended claim.

Having thus described the invention, what we claim is:—

A printing device of the class described comprising a shaft, a roller carried thereby and adapted to rotate therewith, said roller having a longitudinally extending groove provided therein, a printing member extending around the roller, the ends thereof overlapping and being disposed in said groove, means for securing the overlapping ends of the printing member in the groove, said means comprising a piece of wire the intermediate portion thereof extending in said groove and engaging the overlapping end of the printing member, one end of said wire being disposed downwardly adjacent one end of the roller and terminating in a lateral extension, a plate extending around said shaft and fastened to the adjacent end of the roller and being provided with an opening for receiving said lateral extension, the opposite end of the wire being disposed downwardly on the opposite side of the roller and terminating in a hook portion, said hook portion being adapted for detachable engagement with a notch provided in the opposite end of the shaft, and a wire handle having the free ends thereof extending around the ends of the shaft for operating the device.

In testimony whereof we affix our signatures.

HERBERT T. BALDWIN.
LEIGH J. MONSON.
